Attorney

UNITED STATES PATENT OFFICE.

LÉON JOSEPH ALEXANDRE BERTRAND, OF PARIS, FRANCE.

SAFETY CLASP FOR CHAINS OF ALL SIZES AND COLLARS.

Application filed January 12, 1922. Serial No. 528,761.

To all whom it may concern:

Be it known that I, LÉON JOSEPH ALEXANDRE BERTRAND, a citizen of the French Republic, residing at Paris, France, 177 Rue du

5 Temple, have invented a new and useful Improvement in Safety Clasps for Chains of all Sizes and Collars; and I do hereby declare the following to be a full, clear, and exact description of the same.

10 This invention has for its object an improved safety-clasp for collars, neck-chains, bracelets, or other similar articles and, generally, for chains of all kinds and sizes, the said clasp enabling to secure, in a simple and 45 absolutely reliable manner, the junction of the two ends of the chain to which it is applied, when it is desired to close the latter, as well as the loosening of one of the ends of this chain, when it is desired to open it.

15 The invention relates also to certain modified structures of said clasp characterized by various modes of realization of the locking device intended to prevent the opening of the chain, when the clasp is accidentally 50 opened.

The accompanying drawing illustrates, by way of example, a specific embodiment of the invention.

This safety-clasp consists of a hollow ring

30 1, of the well known type, provided, as usual, with an internal closing-spring, but comprising, as a novel feature, a diametral small rod or pin 2. The latter is soldered, or fastened in any other suitable manner, at 55 one of its ends, to the ring 1 close to the orifice A serving as inlet-port for the movable part 1' of the spring-ring 1 on the side opposed to that where is situated the push-button 3.

35 As aforesaid, the pin 2 is fastened only at one of its ends. Between the other end of the same and the internal wall of the ring 1 is provided a clear space or gap B allowing

the free passage, in either direction, of the terminal ring 4 of the chain, when it is desired to close the latter.

In order to bring the terminal ring 4 to the position which it must assume for closing the chain, it is inserted through the gap B and slides at first along the pin 2, then 50 along the spring-ring 1, after having previously forced inwards, through the medium of the push-button 3, the movable part 1' of said ring, which part is thereafter allowed to spring freely outwards, so as to close this ring, as soon as the ring 4 has been engaged around the latter, as shown in the drawing.

For opening the chain, it suffices to liberate the end thereof by bringing back the ring 4 upon the pin 2, then to withdraw said 55 ring through the gap B. The aforesaid pin 2, acting as a locking device, may be straight, as shown in the drawing, but I do not limit the invention to this particular form.

Claims:

1. A safety-clasp for universal use, comprising a ring having an opening, a guard-pin fastened at one end to the inner part of the ring, its other end terminating short of 70 contact with the ring, the guard-pin being rigid.

2. A safety-clasp for universal use, comprising a ring having an opening, a guard-pin fastened at one end to the inner part of the ring, its other end terminating short of contact with the ring, the guard-pin being rigid, and fastened to the ring at a point substantially flush with one edge of the opening, whereby in removal of a chain 75 ring from the ring, the chain ring must be passed successively, over the ring, and the guard-pin.

In testimony whereof I have signed my name to this specification.

LÉON JOSEPH ALEXANDRE BERTRAND.
